US0D1026030S

(12) **United States Design Patent** (10) **Patent No.:** **US D1,026,030 S**
Anderson et al. (45) **Date of Patent:** **** May 7, 2024**

(54) **DISPLAY SCREEN OR PORTION THEREOF WITH A GRAPHICAL USER INTERFACE**

(71) Applicant: **Canva Pty Ltd**, Surry Hills (AU)

(72) Inventors: **Matthew David Anderson**, Newport (AU); **Melanie Joy Perkins**, Surry Hills (AU); **Jesse Walker**, Petersham (AU)

(73) Assignee: **CANVA PTY LTD**, Surry Hills (AU)

(**) Term: **15 Years**

(21) Appl. No.: **29/835,486**

(22) Filed: **Apr. 19, 2022**

Related U.S. Application Data

(62) Division of application No. 29/760,610, filed on Dec. 2, 2020, now Pat. No. Des. 953,357, which is a division of application No. 29/692,367, filed on May 24, 2019, now Pat. No. Des. 907,056.

(57) **CLAIM**

The ornamental design for a display screen or portion thereof with a graphical user interface, as shown and described.

DESCRIPTION

The single view is a front view of a display screen or portion thereof with a graphical user interface.

The outermost broken lines illustrate a display screen or portion thereof and form no part of the claimed design. The remaining broken lines, illustrating portions of the graphical user interface, form no part of the claimed design.

1 Claim, 1 Drawing Sheet
